UNITED STATES PATENT OFFICE.

OLIN A. STRANAHAN, OF CHICAGO, ILLINOIS, AND WILLIAM W. CHURCHILL AND WILLIAM R. RONEY, OF NEW YORK, N. Y., ASSIGNORS TO THE WESTINGHOUSE MACHINE COMPANY, OF PITTSBURG, PENNSYLVANIA, A CORPORATION OF PENNSYLVANIA.

FURNACE.

SPECIFICATION forming part of Letters Patent No. 746,759, dated December 15, 1903.

Application filed December 3, 1902. Serial No. 133,700. (No model.)

To all whom it may concern:

Be it known that we, OLIN A. STRANAHAN, of Chicago, in the county of Cook and State of Illinois, and WILLIAM W. CHURCHILL and 5 WILLIAM R. RONEY, both of New York, in the county of New York and State of New York, have invented certain new and useful Improvements in Furnaces; and we do hereby declare that the following is a full, clear, and 10 exact description thereof, reference being had to the accompanying drawings, and to the letters of reference marked thereon, which form a part of this specification.

This invention relates to improvements in 15 furnaces of that kind which are provided with mechanical stokers or devices for continuously feeding fuel thereto, and more especially to furnaces of the class referred to which have an inclined grate, to the upper 20 end of which the fuel is fed, a fuel-hopper attached to the front wall of the furnace, and a feed-opening in said front wall, through which the fuel passes from said hopper, and a fire-arch over the upper part of the inclined 25 grate, as shown, for instance, in prior United States Letters Patent No. 409,305, granted to W. R. Roney August 20, 1889.

The invention consists in the matters hereinafter described, and pointed out in the appended claims.

In the accompanying drawings, Figure 1 is 30 a view in central longitudinal section of the upper front part of a furnace embodying my invention, showing the fuel-hopper, the upper part of the grate, the arch over said grate, the feed-opening, and associated parts. Fig. 35 2 is a face view of the part of the front wall of the furnace shown in Fig. 1 with the fuel-hopper in vertical section. Fig. 3 is a view 40 in perspective of the detachable throat-plate shown in Figs. 1 and 2 separate from the other parts. Fig. 4 is a detail sectional view of the furnace, taken on line 4 4 of Fig. 1, showing the fire-arch in front elevation. Fig. 45 5 is a detail plan view of the fire-arch.

As shown in said drawings, A A indicate the side walls of the furnace; B, the front wall thereof; C, the upper part of the inclined grate; D, the fuel-hopper; E, the fire-arch, which ex-

tends over the forward part of the grate, and 50 F F fire-brick located between the fire-arch and the front wall of the furnace. The main parts only of the hopper D are shown in the accompanying drawings. The grate C illustrated consists of a series of rocking grate-bars arranged in stepped or overlapped relation, and in connection therewith devices will be provided for giving oscillatory or rocking motion thereto, such as are shown in said prior patent; but inasmuch as any form of 55 grate may be employed a detailed illustration of the grate is deemed unnecessary.

Now, referring to the parts more immediately concerned with the present improvements, the feed-hopper embraces two side 60 plates D' D', which are attached to the front wall of the furnace, a front, and a bottom D², which in the instance shown rests on two inwardly-extending flanges or ledges d d at the lower margins of the side plates. The part of 65 the front wall of the furnace below the hopper is formed by plates B' B⁴ B⁴. The portions of said wall at either end of the hopper are formed by lateral plates B² B², while the portion above the central part of the hopper is formed by an 70 intermediate plate B³. The front wall is provided with a feed-opening formed between the plates B', B² B², and B³. The central portion of the lower margin of said feed-opening is 75 formed by the top edges of the plates B' B⁴ B⁴, which top edges are located at the level of the bottom surface of the bottom plate D² of the feed-hopper, which latter extends over 80 said plate B' to form the dead-plate D⁴ and is bolted to the outer surface of said plates B' and B⁴ B⁴. The feed-opening is made of the same width as the interior of the hopper, and its end margins are formed by the lateral plates B² B², the vertical edges of which are 85 flush with the inner faces of the side walls D' D' of said hopper. The plates B² B² extend inwardly above the said feed-opening, the intermediate plates B' and B³ below and above the opening being shorter than the width of said opening. The top margin of 90 said feed-opening is formed by a separate throat-plate G, which extends the full length of the opening and is attached at its upper 95

edge to the margins of both the lateral plates B² B² and the intermediate plate B³.

As shown in the drawings, the plate B' is attached at its ends to the plates B⁴ B⁴ by means of vertical connecting-bars b b, bolted to both plates. The lateral plates B² B² are provided with sight-openings b' with poker-doors b² and with offset flanges b³ b³ in their lower edges, which overlap the plates B⁴ B⁴, and are also provided on their inner vertical edges above the feed-opening with offset flanges b⁴ b⁴, which overlap the ends of the intermediate plate B³ and to which the latter are bolted. As shown in said drawings, also the side plates D' of the hopper are provided with outwardly-extending flanges d' d², by which said side plates are bolted to the lateral plates B² B² above the level of the feed-opening and to the plates B⁴ B⁴ below the level of the feed-opening.

Now, referring more particularly to the throat-plate G, the same is provided at its upper margin with an outwardly offset flange G', which overlaps the marginal parts of the lateral and intermediate plates B² B² and B³ and through which are inserted bolts for securing the throat-plate to said intermediate and lateral plates. The offset construction of the flange G' brings the main or lower part of the throat-plate in the same plane with the furnace-wall above the same when the parts are assembled. On its rear or inner face said throat-plate is provided with a horizontal inwardly-projecting flange G², which serves as a support for the outer ends of the fire-brick F, which latter are provided with grooves f to engage said flange. The inner ends of said fire-brick are shown as supported from the front wall of the furnace by means of a metal bracket f', as shown in said prior patent, No. 409,305. The lower edge of the said throat-plate is provided with a plurality of slots or notches g g, which are open at their lower ends and extend upwardly from the lower edge of said plate into the body of the same. Said slots or notches form a series of projections or fingers on the lower margin of the plate. The purpose of said notches is to prevent the throat-plate from being warped or distorted by the action of heat on the lower edge of the plate, which is the part of the plate most exposed to the heat from the burning fuel at the top or upper part of the grate.

The portion of the front wall of a furnace of the kind herein shown which is exposed to the destructive action of heat from the fire is that above the fuel-feed opening and adjacent to or in contact with the fire-brick F. In a furnace in which the front wall is made of iron in the usual manner, as shown, for instance, in said prior patent, No. 409,305, the front wall above the feed-opening has been found to become deteriorated or burned out by the excessive heat to which such part is exposed much more rapidly than other parts of the said front wall. In such a fur-

nace, therefore, the burning out of this part of the front wall frequently occurs and makes extensive work necessary in the way of repairs, because requiring the renewal of the castings or plate forming the entire upper part of the front wall. The construction herein illustrated has the important advantage that the detachable throat-plate, which is the only part exposed to the destruction by heat, may be readily removed and replaced by a new one. Such construction has the further advantage that the flange which supports the fire-brick, being formed on or attached to the throat-plate, is removable with the latter, so that said flange, which is liable to deterioration nearly to the same extent as the part of the wall below it, may be removed and renewed with the throat-plate.

The presence of the slots g g in the throat-plate is important, because by preventing the warping or distortion of the plate and the flange thereon it greatly prolongs the life of said plate and prevents the fire-brick from being loosened or displaced, as is liable to occur if the plate becomes warped or bent by heat.

The fire-arch illustrated in the accompanying drawings embraces improved features of construction, as follows: Said fire-arch is inclined downwardly and inwardly or in the same general direction as the inclination of the grate below it. Said fire-arch is, moreover, made of stepped form on its under surface, so as to present a plurality of ridges which extend across the furnace and form shoulders or abrupt surfaces facing toward the front of the furnace. As shown and preferably constructed, the ridged lower surfaces of the fire-arch are so constructed that a sectional view of the arch will show alternating horizontal and vertical faces, so that the forwardly-facing shoulders thereon have flat and vertical faces. Moreover, the spring of the arch is greater at the inner than at the outer part thereof, or, in other words, the arch is flatter in its part near the front of the furnace than at its rear part.

The features of construction in the arch above referred to are obtained by making the arch of a series of rings or rows of fire-brick shaped like the voussoirs of an arch, each row or ring extending from side to side of the furnace and the several rows or rings being arranged in stepped relation, so as to give a downward and inward inclination to the arch as a whole. In the particular construction illustrated the two outermost rows or rings E' E² and the innermost rings E³ are shown as made thicker from front to rear than the intermediate rings E⁴ E⁴, which are of the same thickness. The outermost ring E' is shown as made flatter than the ring E², while the latter is flatter than the intermediate rings E⁴, which latter are alike in shape. The rows E' E² and the adjacent or outermost of the intermediate rows E⁴, moreover, have their under surfaces at the crown of the

arch at the same level, so that these rows are flush with each other at the center of the furnace, but diverge at their ends, so as to present flat vertical shoulders or faces between them at such ends. The vertical surfaces or shoulders between the several rings E^4 E^4 and between the innermost one of said rings E^4 and the innermost wider ring E^3 are of substantially equal width from side to side 5 of the furnace, Fig. 4. The front and rear faces of the bricks in the several rings are vertical and parallel with each other. In order to strengthen the arch and make it more durable and substantial, the rings 10 comprising the same are connected or bonded at the crown of the arch through the introduction of fire-brick e e' of double thickness or of sufficient length from front to rear to extend through two adjacent rings.

20 The advantage gained by making the inner or lower face of the arch inclined and of stepped or shouldered form is that this construction prevents the products of combustion or gases arising from the combustion 25 of the coal at the top of the grate from passing so quickly or rapidly along the fire-arch as to pass the rear margin of the same without complete combustion thereof or with the accompanying smoke unconsumed. This re-

30 tarding of the rearward movement of such products of combustion is due mainly to the stepped form of the inclined lower surface of the arch, the shoulders of which produce an eddying or swirling motion therein, tending to 35 interrupt the direct rearward flow of the gases and retaining them beneath the arch long enough to insure the complete combustion of the smoke. This result is aided or assisted by the shape of the arch which, having greater 40 convexity at its rear part than at its front or flatter end, tends to throw or deflect inwardly and downwardly the gases which rise into contact with the arch at the sides of the same. By making the arch flatter at its forward than 45 at its rear end, moreover, the sides of the arch adjacent to the front plate are elevated, so as to leave spaces for the introduction of a poker through the poker-opening b^2 at the sides of the fuel-openings and also to permit 50 inspection of the fire through the sight-openings there located. An advantage is also gained by the stepped construction in the arch described by reason of the fact that this construction in an inclined arch is better, 55 stronger, and more durable than one in which the arch-rings are disposed obliquely, it being obvious that each of the sets or rings of the fire-arch composing the arch are in vertical planes instead of being inclined, as in 60 the arch shown in said prior patent hereinbefore referred to the action of gravity has no tendency to displace or overthrow the brick forming the arch.

We claim as our invention—

65 1. The combination with the metal front wall of a furnace provided with a feed-opening, and a fire-arch comprising a row of fire-

brick which are supported on said front wall, a throat-plate which extends across the feed-opening and forms the top margin thereof, 70 said throat-plate being detachably secured at its upper edge to said front wall, and means for supporting said fire-brick on the said front wall, consisting of an inwardly-extending, integral flange on the inner face of 75 the said throat-plate, on which the forward ends of said fire-brick rest, and brackets attached to the front wall and adapted to engage and support the rear ends of said fire-brick. 80

2. The combination with the front wall of a furnace and a fuel-hopper thereon, said front wall having a feed-opening the side and lower margins of which coincide with the bottom and side walls of the fuel-hopper, and 85 the portions of which adjacent to the feed-opening consist of two lateral plates which project inwardly over the lateral portions of said feed-openings, and to which the side walls of the fuel-hopper are attached, and an 90 intermediate plate which has overlapping relation at its ends with and is bolted at its ends to the inner margins of the said lateral plates, and a throat-plate which extends the full width of the feed-opening and forms the 95 top margin thereof, said throat-plate having overlapping relation at its upper edge both with the lateral and intermediate front plates, and being detachably secured to said parts. 100

3. The combination with the metal front wall of a furnace provided with a feed-opening, a fire-arch embracing a row of fire-brick which is located adjacent to said front wall above the said feed-opening, and a throat-plate which extends across the top of the 105 feed-opening and is detachably secured at its upper margin to said front wall; said throat-plate being provided on its rear surface above its lower edge with an inwardly-projecting flange and the forward ends of the fire-brick 110 being provided above their lower faces with notches to engage said flange, and being extended, below said flange, into contact with the rear surface of the throat-plate.

4. The combination, with the metal front 115 wall of a furnace provided with a feed-opening, a fire-arch embracing a row of fire-brick which is located adjacent to said front wall above the feed-opening, and a throat-plate which extends across the feed-opening and is detachably secured at its upper margin to the lower margin of said front wall, said throat-plate being provided on its rear surface above its lower edge with an inwardly-projecting flange 120 125 and the forward ends of the fire-brick being provided above their lower faces with notches to engage said flange and being extended, below the flange, into contact with the inner face of the throat-plate, the throat-plate being extended at its lower margin below the fire-brick, and having in its margin which so 130 extends below the fire-brick, a plurality of slots or notches.

5. The combination with the metal front wall of a furnace of a fire-arch consisting of a flat front portion which is attached to and supported solely by said front wall, and a 5 rearwardly and downwardly inclined rear portion of sprung form, which is supported on the side walls of the furnace; said rear or sprung portion of the arch being of less rise or curvature at its front than at its rear part.
10. 6. A sprung fire-arch for furnaces which is rearwardly and downwardly inclined and has less rise or curvature at its front than at its rear part.
15. 7. A sprung fire-arch for furnaces which is rearwardly and downwardly inclined, is stepped on its under surface and has less rise or curvature at its front than at its rear portion.
20. 8. A fire-arch for furnaces which is inclined downwardly from the front toward the rear of the furnace and comprises a plurality of sets or rows of arch-brick arranged in stepped relation, one or more of the rows at the front of the arch having less curvature than those 25 of the rear thereof, so that the arch is flatter or has less rise at the front than at the rear of the furnace.
25. 9. A fire-arch for furnaces which is inclined downwardly from the front toward the rear 30 of the furnace and comprises a plurality of sets or rows of arch-brick disposed in stepped relation, one or more of the rows of brick at

the front of the arch having less curvature than the rows at the rear of the arch, and two or more of the rows of brick at the front of the arch having their lower faces, at the crown of the arch, arranged in the same horizontal plane.

35. 10. A fire-arch for furnaces which is inclined downwardly from the front toward the rear 40 of the furnace, and comprises a plurality of rows of arch-brick arranged in stepped relation, the row of fire-brick at the front of the arch being of less curvature than those at the rear, and one or more intermediate rows between said front row and the rear rows being 45 of intermediate curvature.

In testimony that we claim the foregoing as our invention we affix our signatures, in presence of witnesses, this 16th day of January, 50 A. D. 1901.
